UNITED STATES PATENT OFFICE

107,882

DESIGN FOR AN ASSIST CORD

George W. Nesbitt, Sycamore, Ill.

Application November 23, 1937, Serial No. 73,130

Term of patent 14 years

To all whom it may concern:

Be it known that I, George W. Nesbitt, a citizen of the United States, residing at Sycamore, in the county of De Kalb and State of Illinois, have invented a new, original, and ornamental Design for an Assist Cord, of which the following is a specification, reference being had to the accompanying drawing, forming part thereof.

Figure 1 is a front elevation of an assist cord showing my new design;

Figure 2 is a side elevation thereof;
Figure 3 is an enlarged fragmentary front elevational view of one of the hand grips shown in Figure 1; and

Figure 4 is a side view of Figure 3.

I claim:

The ornamental design for an assist cord, as shown.

GEORGE W. NESBITT.
